ABSTRACT OF THE DISCLOSURE

The illustrative embodiment discloses a somewhat cylindrical tank for containing beverage and incorporating a spigot, which tank is snugly received in an insulating container formed primarily of cellular plastic for example. The container defines a cavity adjacent the tank for receiving solid coolant, e.g. ice. The cavity-defining portion of the container provides a stand for holding the tank horizontal so that access to the spigot is convenient through a displaceable transparent slide.

The present invention relates to a portable cooling unit and more specifically to a unit for conveniently and easily refrigerating a fluid-containing tank, by means of ice or other independent cooling medium.

The storage and transportation of various liquids, as beverages in pressure vessels has been wide spread practice for many years. However, somewhat recently, improved tank or keg structures have been developed that are self-contained and self-generating. That is, these tanks dispense liquid under pressure and are independent of any auxiliary apparatus.

In the transportation and storage of these improved tanks, it is generally desirable that they are maintained continuously refrigerated, and of course, they definitely should be refrigerated during periods of use. This consideration becomes somewhat of a problem when using the tank in locations where refrigerated storage capacity is limited. Specifically for example, it may be a problem to cool a pressure tank containing a beverage over any extended time period while camping, picnicing or occupying a small boat.

For many years, beverage tanks or kegs have been refrigerated during a period of use by simply placing them in a bucket or other container filled with ice. However, the improved portable pressure tanks as referred to, are generally cylindrical in form and must rest in a horizontal position while in use. Of course access must be provided to a spigot which is located in the end of the cylinder. It is therefore a problem to hold ice or other coolant on the tank or keg while maintaining a clean, dry, stable, arrangement.

Various forms of refrigeration packages or containers have been previously proposed for use with improved beverage tanks or kegs as considered above. Initially, one might consider simply placing the keg on a cake of ice within an insulated container. However, in such an arrangement, as the ice block melts, space develops within the container so that the tank can move and shift to damage the container or place the spigot where it is inaccessible.

In an alternative arrangement, if the tank is clamped in position within the container, the ice soon melts away from the tank developing an insulating space between the ice and the tank resulting in ineffective cooling. To avoid this occurrence, prior structures have provided a space above the tank in which ice can be placed for continuous contact with the tank and which space is drained to remove water from the melting ice. However, these arrangements tend to be top heavy and are therefore rather unstable. Furthermore, effective containment and draining of water from the ice presents a perpetual prob-

2

lem. Still further, these structures are generally rather expensive to manufacture, cumbersome to handle and are not particularly attractive.

It is therefore an object of the present invention to provide an improved portable structure for containing a rigid tank, which structure also contains a coolant as ice for example, and which incorporates an arrangement for preserving contact between the ice and the tank, and furthermore effectively contains water produced from melting ice.

Another object of the present invention is to provide an improved portable structure for containing a rigid tank while cooling the tank, as with ice, which structure may be economically manufactured, is attractive in appearance, and is stable in use when free standing.

A further object of the present invention is to provide an improved portable structure for containing a beverage keg, which is effective to refrigerate the keg while stably supporting the keg and currently containing ice which continues to be effective throughout the melting process, which structure also effectively contains water as it is produced from the ice.

Still a further object of the present invention is to provide a portable structure that may be easily and conveniently handled, which structure is for containing a rigid tank of pressurized beverage, and which structure defines a cavity to snugly hold the tank in a fixed position, and further defines a cavity below the tank for containing ice, the latter cavity also including means for biasing the ice upward into continual contact with the tank.

These and other objects and advantages of the present invention will become apparent from a consideration of the following, taken in conjunction with the drawings, wherein:

FIGURE 1 is a perspective view of the structure incorporating the principles of the present invention;

FIGURE 2 is a vertical sectional view taken along line 2—2 of FIGURE 1;

FIGURE 3 is a horizontal sectional view taken along line 3—3 of FIGURE 1;

FIGURE 4 is a vertical sectional view taken along line 4—4 of FIGURE 1; and

FIGURE 5 is a front elevation of the structure of FIGURE 1.

Referring initially to FIGURE 1, there is shown a simulation of a traditional wooden barrel 10 held on a mating support stand 12. At the forward end of the barrel 10 (as shown) a transparent slide 14 may be displaced to provide access to a tap 16 as shown in FIGURE 5 for drawing liquid from the tank 18 (FIGURE 2) that is held snugly within the barrel 10. The tank and its contents are cooled by ice 20 (FIGURE 2) which is biased upwardly into engagement with the keg or tank 18 by a resiliently-deformable sponge-like pad 22. As a result, the contents of the keg or tank 18 is effectively refrigerated by the ice 20 and is insulated by containment in the barrel 10.

Considering the structure in greater detail, the simulated barrel 10 snugly receives the keg or tank 18 and is formed integral with the stand 12 in two mating sections. An upper generally-semi-cylindrical section 24 (FIGURE 2) has an internal flange 26 extending about its edge, which flange is matingly received in a groove 28 extending about the edge of a lower section 30 simulating the lower half of the barrel 10 and the stand 12. That is, the lower half of the barrel 10 and the stand 12 comprise the integral section 30. Thus, when mated, the sections 24 and 30 define a somewhat-cylindrical cavity 32 for snugly containing the generally-cylindrical keg or tank 18. Furthermore, the bottom of the cavity 32 opens into a somewhat parallelepiped cavity 34 defined by the lower

section 30, the bottom of which contains the resiliently deformable pad 22 carrying ice 20.

The rear end 35 (FIGURE 4) of the barrel 10 and the forward end 36 are provided by the semi-circular ends of the upper and lower sections 24 and 30. The forward end 36 contains a vertically movable slide 14. The slide 14 is transparent and is received in grooves 38 (FIGURE 3) to be matingly received in the both halves of the end 36.

The selection of materials for the structure is quite significant. Specifically, the sections 24 and 30 may be molded of expandable polystyrene which has good insulation characteristics, is light in weight, and adequately strong in view of the manner in which the structure is developed. In forming the sections, the configuration of the barrel 10 (FIGURE 1) is accomplished by surface molding the annular hoops 39 and 40 and the grooves 42 traversing the length of the barrel and spaced apart to accomplish the simulation of barrel staves 44. The sections 24 and 30 may be molded of expanded material in relatively simple molds and furthermore, the structure is relatively strong, attractive and very effective as a portable refrigeration unit.

The molded form of the unit is relatively strong. This consideration is particularly true when a rigid keg or tank 18 is contained within the cylindrical cavity 30. During such times, the internal support provided by the tank 18 renders the entire unit relatively rigid. Regarding the strength of the unit, some additional reinforcement is provided to the stand 12 by a layer 46 (FIGURE 2) of paper, plastic, or other material which may be faced with the simulated wood pattern. The lamination of the layer 46 over the support stand 12 provides improved rigidity and serves as a protective barrier for the stand.

The slide 14 may be formed of various hard surface materials, however, as indicated, in the disclosed embodiment a transparent plate is employed. Specifically, it has been found desirable to form the slide 14 (FIGURE 1) of transparent dye-cut acetate provided with non-slip grooves or serrations 48. The use of a hard surface material in the slide 14 accomplishes a smooth sliding relationship between that member and the grooves 38 (FIGURE 3). Furthermore, the fact that the slide 14 is transparent makes the interior of the unit and the tap 16 visible. Therefore, any leakage from the tap 16 or other difficulties which can arise can be readily observed so that corrective action can be taken.

In the manufacture of the unit as described, the sections 24 and 30 may be molded of expanded plastic having good insulating characteristics as well known in the prior art. The material may be colored or tinted to enhance the simulation of the barrel 10. After these sections have been molded, they may require some trimming and fitting to accomplish a snug fit of the flange 26 in the groove 28 whereby to define the cavity 32 for the tank 18. The manufacturing operation may then be completed by applying the layer 46 adhesively to the exterior stand 12, inserting the slide 14 and positioning the mat or pad 22 within the cavity 34. In one arrangement, the pad 22 comprises resiliently-deformable sponge rubber or plastic, which is adhesively secured to the interior surface 50 of the cavity 34. Such material has been found effective not only to force the ice 20 up into continual contact with the exterior lower surface of the tank 18, but also to contain water from the melting ice avoiding sloshing of the water about within the cavity 34. However, various other materials and structures may also be employed to bias the ice upwardly to engage the tank. Specifically, for example, the pad 22 may comprise an inflatable pillow to accommodate resilient distortion or compression within the cavity 34 in which entrapped air biases the ice 20 upwardly into engagement with the tank 18.

In using the structure hereof, the upper section 24 is lifted from the lower section 30 and ice 20 is placed in the cavity 34. As the ice is placed in position it may be formed in somewhat of a mound at the center to extend

into the cavity 32. Next, the tank 18 (normally cold) is set over the ice and pressed into mating engagement with the cylindrical surfaces of the section 30. Thereafter, the upper section 24 is mated to the lower section 30 and the unit is ready for transportation or use.

In transporting the unit, it is to be noted that the stand 12 containing the ice 20 is somewhat weighted by the ice so that the unit does not tend to be top heavy. Furthermore, the tap 16 may be continually observed through the slide 14, to assure that it is not leaking or partly opened. Of course, as the unit is transported or used it is an effective refrigeration structure because the ice 20 is maintained in continual contact with the tank 18 and effective insulation is provided all around the tank 18. Over a prolonged period of transporting or using the apparatus, the ice 20 gradually melts to preserve a low temperature for the tank 18 with the accumulation of water in the cavity 34. However, the water in the cavity is effectively contained by the structure of the stand 12 and may be somewhat entrapped within the sponge-like materials forming the pad 22. That is, as the ice 20 (FIGURE 2) melts gradually, producing water, it relieves the pad 22 permitting the pad to expand and thereby absorb the water. As a result, of this mutual coaction, the ice 20 is biased into continual contact with the tank 18 and the produced water is effectively entrapped in the pad 22. The entrapment of the water avoids sloshing and permits the unit to be easily carried and transported.

Another feature of the structure hereof resides in its attractive, clean and well-balanced traditional appearance. Of course, various other features and advantages for the structure will be readily apparent to those skilled in the art. Furthermore, certain modifications from the illustrative embodiment will also be apparent; therefore, the scope hereof is not to be limited in accordance with the illustrative embodiment but rather shall be interpreted in accordance with the appended claims.

What is claimed is:

1. A portable refrigeration unit for cooling fluid with a solid coolant, comprising:
a rigid tank of somewhat cylindrical configuration for containing said fluid and having a spigot means for drawing fluid therefrom;
an insulating container for snugly containing said tank substantially enclosed and furthermore, defining a cavity contiguous to said tank for receiving said solid coolant, and having a displaceable slide section for providing access to said spigot means of said tank; and
means for biasing said solid coolant into engagement with said rigid tank.
2. A refrigeration unit as defined by claim 1 wherein said insulating container portion defining said cavity affords a stand for supporting said integral unit whereby to dispose said substantially cylindrical tank axially horizontal.
3. A refrigeration unit according to claim 2 wherein said insulating container primarily comprises opaque cellular plastic and said displaceable slide section comprises a transparent member.
4. A structure according to claim 3 wherein said solid coolant comprises ice and said means for biasing comprises a water absorbent member.
